(57) **CLAIM**

The ornamental design for a sidewall for a tire, as shown and described.

DESCRIPTION

FIG. 1 is a perspective view of a full tire including the sidewall for a tire of the present application; and, FIG. 2 is a side view thereof.

The other side of the tire is unadorned. The broken lines shown illustrate portions of the sidewall for a tire that form no part of the claimed design.

1 Claim, 2 Drawing Sheets

FIG. 1

FIG. 2
